UNITED STATES PATENT OFFICE.

EUGENE ROBERTS AND ANGUS H. GIBSON, OF SALT LAKE CITY, UTAH, ASSIGNEES TO SUGAR CENTRIFUGAL DISCHARGER CO., OF SALT LAKE CITY, UTAH, A CORPORATION OF UTAH.

DISCHARGER FOR CENTRIFUGAL BASKETS.

1,377,141.

Specification of Letters Patent.

Patented May 3, 1921.

Application filed December 17, 1917. Serial No. 207,432.

To all whom it may concern:

Be it known that we, EUGENE ROBERTS and ANGUS H. GIBSON, citizens of the United States, and residents of Salt Lake City, county of Salt Lake, State of Utah, have invented certain new and useful Improvements in Dischargers for Centrifugal Baskets, of which the following is a specification.

This invention relates to devices for discharging the walled-up sugar from the basket of a centrifugal machine after the operation of separating the juice or syrup from the solid sugar has been completed.

The present invention relates to the same general type of discharger as that shown in the Roberts and Gibson Patent No. 957715, granted May 10th, 1910. As in the case of said patented invention, the plow supporting spindle is movable vertically for the purpose of discharging the sugar and also for removing the plow out of the basket. The present invention comprises improved means for supporting the plow so as to render more convenient and easy the removal of the plow from the basket, and at the same time making it impossible for the plow to be accidentally jolted off from its idle position on top of the spindle curb surrounding the basket.

To this end, the invention comprises generally speaking, a vertically movable plow spindle with its attached plow mounted in a supporting member that is partially rotatable about a horizontal axis so that when the plow is raised it can be swung over from vertical to substantially horizontal position above the curb where it is not only out of the way but is secure from being accidentally jolted back into the basket by the vibration of the machinery. A further advantageous feature of the invention resides in the arrangement by which the vertically movable oscillatory plow is supported in a fixed or stationary member for operation

instead of being carried by a horizontally swinging arm whose position may be affected by pressure exerted against the plow to disturb the accurate positioning of the plow when in service.

These and other features of the invention will be more particularly described in this specification and will be defined in the claims annexed hereto.

In the accompanying drawings there is

illustrated the preferred arrangement embodying the principles of this invention in which:

Figure 1 is a plan view, with the fixed bracket or casing partly broken away to show the interior construction of the supporting member.

Fig. 2 is an elevation showing in dotted lines the operative and idle position respectively of the plow.

Fig. 3 is a vertical central section of the plow supporting and elevating means.

Fig. 4 is a vertical section showing the means for limiting movement of the plow supporting member.

According to the practice illustrated in the drawing we mount on the curb or casing *a* which surrounds the centrifugal basket *b* a horizontal tubular bracket *h* having suitable projections or flanges by which it is bolted to the top of the curb. In the horizontal cylindrical bore of the bracket *h* is rotatably mounted an elongated sleeve *g* which at its inner end is formed with an enlarged head *g'* provided with a circular cavity or chamber for inclosing a pinion *f'* secured to the end of a horizontal operating shaft *f* which is mounted in the central bore of the sleeve *g*. The head *g'* is also formed with a bore or cylindrical passage located at one side of the pinion chamber and extending transversely to the axis of the shaft and of the sleeve and partly intersecting the side wall of said pinion chamber to allow the teeth of the pinion to project into said transverse passage to engage the teeth *e'* of a hollow rack bar *e* that is mounted to slide up and down in said transverse passage in the head *g'* for a purpose to be explained.

Within the sliding hollow rack bar or sleeve *e* is mounted a rotatable spindle or rod *d* to whose lower end is secured the plow *c* which normally serves to cut down and scrape away the sugar or other material walled up on the inside of the basket *b*. To the upper end of this plow spindle is secured a hand lever *d'* by which the plow may be operated to swing toward or away from the circumferential wall of the basket *b*.

On the outer end of the horizontal shaft *f* is secured a hand wheel *f''* by which the shaft is rotated in order to raise or lower the plow spindle *d* and its attached plow *c*

through the interconnecting slidable rack-sleeve *e* and the pinion *f*.

Now as the rack sleeve *e* extends at right angles to the horizontal rotatable sleeve *g* and is carried by said sleeve *g*, it is clear that the rotation of the bearing sleeve *g* in its containing tubular bracket *h*, through an arc of 90° in a contra-clockwise direction, will act to swing the rack sleeve *e* and the plow supporting spindle *d* from a vertical position for normal use to a horizontal or inoperative position as indicated by the dotted line showing of the rack sleeve above the curb in Figs. 1 and 2.

15 That is, the simple turning of the sleeve *g* one quarter turn from operative position of the plow serves to lift the plow clear out of the top of the basket. To do this the hand wheel must first be turned in a contra-clockwise direction to raise the plow and the plow must be swung toward the center of the basket sufficiently to allow it to clear the overhanging rim of the basket.

To support the pressure or thrust of the 25 revolving wall of sugar against the tip of the plow when the plow is in use we provide a suitable stop member *g*² projecting from the head *g*' of the tubular sleeve to engage a shoulder *h*' projecting from the inner end 30 of the tubular bracket *h*, as clearly shown in Fig. 1. This limits the rotative movement of the sleeve in a clockwise direction while allowing the sleeve to be rotated in the opposite direction when it is desired to withdraw 35 the plow from the basket.

The stop collar *g*⁴ secured to the sleeve *g* by a set screw *g*⁵ serves as an end thrust bearing member to prevent axial displacement of the sleeve *g* in the bracket *h*.

40 By the above-described arrangement not only is the plow very easily and conveniently removed and re-inserted into the basket and held securely against accidental jarring back into the basket when in idle 45 position above the curb, but furthermore, the plow when in operative position has but a single swinging movement that is toward and away from the periphery of the basket about a vertical axis. The movement of the 50 plow and sleeve about their horizontal axis under the pressure exerted by the revolving wall of sugar against the tip of the plow is limited by means of the stop *g*₂ so that the plow is held firmly against any lateral 55 swinging movement of its support when in use. In other words, the thrust or pressure of the sugar against the plow is firmly sustained by the plow supporting structure and thus a more accurate and reliable position- 60 ing of the plow is permitted.

What we claim is:

1. A discharger for centrifugal baskets embracing in combination a fixed supporting bracket, a horizontal sleeve mounted therein 65 to oscillate about its horizontal axis and hav-

ing a vertically bored member for supporting the vertical plow-supporting spindle to permit both axial and oscillatory movement of said plow-supporting spindle when in operative position for use, a stop member co-operating with said horizontal sleeve to maintain the spindle in working position against the thrust of the material being discharged from the revolving basket, said sleeve being revoluble in an opposite direction to permit the quick removal of the plow from the basket, substantially as described.

2. In a discharger for centrifugal machines the combination of a discharger plow and vertical oscillatory spindle to which said plow is secured, means for raising and lowering the plow and a supporting member arranged to firmly support the plow against the thrust of the revolving wall of sugar, said supporting member being rotatable to permit the plow and its supporting spindle to be swung into idle position above the basket, substantially as described.

3. In a discharger for centrifugal machines the combination of a fixed bracket, a horizontal sleeve member revolvably mounted in said bracket to have partial rotation about a horizontal axis, a vertically slidable plow supporting spindle carried by said horizontal sleeve whereby said plow spindle may be swung from vertical operative position to horizontal idle position above the basket, and means for controlling the operative position of the plow when in use, substantially as described.

4. In a discharger for centrifugal baskets the combination of a discharger plow, a vertical supporting spindle to which said plow is secured, said spindle being mounted to oscillate about its vertical axis and also to pivot about a horizontal axis to permit its removal from the basket and being vertically movable when in operative position, and means for controlling the operative position of said spindle and plow during the discharging operation, substantially as described.

5. In a discharger for centrifugal baskets the combination of a plow and its supporting spindle, said spindle being supported to be turned about two angularly disposed axes, means for actuating said spindle in order to properly position the plow during the discharging operation and means for limiting movement of the plow in one direction about one of its axes when the plow is in active use, substantially as described.

6. In a discharger for centrifugal baskets the combination of a supporting member mounted to turn about a substantially horizontal axis, a discharger plow, a vertical spindle to which said plow is secured, said spindle being movable about its own vertical axis, and also movable longitudinally of its axis, a stop device for preventing

movement of said supporting member by the thrust of the material in the basket against the plow while permitting rotation of the supporting member in the reverse direction for the restoring of the plow to idle position above the basket, substantially as described.

7. In a discharger for centrifugal machines the combination of the plow and its vertical supporting spindle, a supporting member for operatively supporting the said spindle and plow, said supporting member being movable about a horizontal axis, a bracket in which said supporting member is mounted, a stop device in said supporting member arranged to engage a fixed shoulder or abutment on the bracket in order to prevent the plow and its spindle from being moved out of operative position by the thrust of the material against which the plow is acting, substantially as described.

8. A discharger for centrifugal baskets embracing in its construction a fixed bracket, a horizontal sleeve rotatably mounted in said bracket, a plow actuating shaft mounted inside said sleeve to raise and lower the plow, a vertical oscillatory spindle, a plow secured thereto and intermediate connecting means for operatively connecting the plow actuating shaft and the plow supporting spindle, substantially as described.

9. In a discharger for centrifugal ma-

chines the combination of the vertical oscillatory spindle, a plow secured to the lower end thereof to engage and cut away the material walled up in the interior of the basket, a horizontal shaft having operative connection with said spindle to raise and lower the spindle axially, an oscillatory sleeve for operatively supporting said spindle and said shaft, means for holding said sleeve normally against turning due to the thrust of the material against the plow while permitting rotation of the sleeve in the reverse direction to permit the removal of the plow from the basket, substantially as described.

10. In a discharger for centrifugal machines, a cylindrically bored bracket, a bearing sleeve mounted in the bore of said bracket to have rotative movement therein, said bearing sleeve having a head formed with a laterally disposed bearing passage extending transversely of the axis of said sleeve, plow supporting means mounted to slide endwise in said bearing passage, an operating shaft mounted in said bearing sleeve and having operative connection with the slidable plow supporting means to raise and lower the same, substantially as described.

In witness whereof, we have subscribed the above specification.

EUGENE ROBERTS.
ANGUS H. GIBSON.
